Des. 1758

Egbert S. Richards, of Attleboro, Mass.
Letters Patent No. 1758, dated May 5, 1863.

The schedule referred to in these Letters Patent and making part of the same.

To all whom it may concern:

Be it known that I, Egbert S. Richards, of Attleboro, in the Commonwealth of Massachusetts have invented or produced a new and original design for a breast-pin or ear-drop, and I do hereby declare that the following specification taken in connection with the drawing, making a part of the same is a full, clear and exact description thereof.

The purpose of the new design exhibited in the accompanying drawings is to relieve by contrast of color the breast-pin or ear-drop, the body of which is made of glass, jet, wood, vulcanized rubber or other similar material, and to present the appearance of inlaid work. I therefore make the arms of these articles of ornament which are cruciform as shown fluted, the channels being parallel with the axes. In these channels I place metallic wires of a contrasting color as exhibited in the drawings.

The wires at one end are attached to, or are brought in contact with the tips b. b. b. b. and at the other end meet the centre piece A so that the result is a design for these articles of ornament which presents the appearance of a skeleton cross of gold or other metal, enclosing a body of jet, colored glass or material other than metal.

What I claim as new and desire to secure by Letters Patent, is

The ornamental design for a breast-pin, ear-drop or similar ornament herein described and represented in the accompanying drawing.

Witnessed
B. F. Thurston,
Esq. }
Prof. H. Peabody.

Egbert S. Richards.
